US0D1063006S

(12) **United States Design Patent** (10) **Patent No.:** **US D1,063,006 S**
(45) **Date of Patent:** **** Feb. 18, 2025**

(54) **PIPE FITTING**

(71) Applicant: **Mustang Sampling, LLC**,
Ravenswood, WV (US)

(72) Inventors: **Kenneth O. Thompson**, Ravenswood,
WV (US); **Kevin Warner**, The
Woodlands, TX (US); **William C.**
Paluch, Jersey Village, TX (US)

(73) Assignee: **Mustang Sampling, LLC**,
Ravenswood, WV (US)

(**) Term: **15 Years**

(21) Appl. No.: **29/859,810**

(22) Filed: **Nov. 14, 2022**

Related U.S. Application Data

(62) Division of application No. 35/002,011, filed on Mar.
16, 2021 (U.S. filing date under 35 U.S.C. 384), and
having an international filing date of Mar. 16, 2021,
now Pat. No. Des. 973,849.

(57) **CLAIM**

The ornamental design for a pipe fitting as shown and described.

DESCRIPTION

FIG. 1 is a perspective view of a pipe fitting design of the invention.

FIG. 2 is a top view of the pipe fitting design of FIG. 1.

FIG. 3 is a bottom view of the pipe fitting design of FIG. 1.

FIG. 4 is a front view of the pipe fitting design of FIG. 1.

FIG. 5 is a back view of the pipe fitting design of FIG. 1.

FIG. 6 is a left view of the pipe fitting design of FIG. 1; and,

FIG. 7 is a right view of the pipe fitting design of FIG. 1.

The evenly spaced broken lines in FIGS. 2 and 3 depict portions of the pipe fitting that form no part of the claimed invention.
